(57) **CLAIM**

The ornamental design for a bowl, as shown and described.

DESCRIPTION

The patent or application file contains a least one drawing executed in color. Copies of this patent or patent application publication with color drawings will be provided by the Office upon request and payment of the necessary fee.

FIG. 1 is a top, front, right perspective view of a first embodiment of a bowl showing my new design;

FIG. 2 is a front view thereof, wherein the rear view is a mirror image of FIG. 2;

FIG. 3 is a right side view thereof, wherein the left side view is a mirror image of FIG. 3;

FIG. 4 is a top view thereof;

FIG. 5 is a bottom view thereof;

FIG. 6 is a cross-sectional view of the bowl taken along line 6-6 in FIG. 4;

FIG. 7 is a top, front, right perspective view of the second embodiment of a bowl;

FIG. 8 is a front view thereof, wherein the rear view is a mirror image of FIG. 8;

FIG. 9 is a right side view thereof, wherein the left side view is a mirror image of FIG. 9;

FIG. 10 is a top view thereof;

FIG. 11 is a bottom view thereof;

FIG. 12 is a top, front, right perspective view of a third embodiment of a bowl;

FIG. 13 is a front view thereof; wherein the rear view is a mirror image of FIG. 13;

FIG. 14 is a right side view thereof, wherein the left side view is a mirror image of FIG. 14;

FIG. 15 is a top view thereof;

FIG. 16 is a bottom view thereof;

FIG. 17 is a top, front, right perspective view of a fourth embodiment of a bowl;

FIG. 18 is a front view thereof, wherein the rear view is a mirror image of FIG. 18;

(Continued)

FIG. 19 is a right side view thereof, wherein the left side view is a mirror image of FIG. 19;
 FIG. 20 is a top view thereof;
 FIG. 21 is a bottom view thereof;
 FIG. 22 is a top, front, right perspective view of a fifth embodiment of a bowl;
 FIG. 23 is a front view thereof, wherein the rear view is a mirror image of FIG. 23;
 FIG. 24 is a right side view thereof, wherein the left side view is a mirror image of FIG. 24;
 FIG. 25 is a top view thereof; and,
 FIG. 26 is a bottom view thereof.
